UNITED STATES PATENT OFFICE.

DAVID H. BROOK, OF DAYTON, OHIO.

TOY.

1,331,617.

Specification of Letters Patent.

Patented Feb. 24, 1920.

Application filed May 19, 1919. Serial No. 298,085.

To all whom it may concern:

Be it known that I, DAVID H. BROOK, a citizen of the United States, residing at Dayton, in the county of Montgomery and 5 State of Ohio, have invented certain new and useful Improvements in Toys, of which the following is a specification.

This invention comprises an improvement in toys and has a more specific reference to 10 toy air-ships.

The object of the invention is to provide a toy of this character that possesses in miniature form the general and specific visible features of a full size operative air- 15 ship.

A further object of the invention is to provide means whereby the production of such a toy is at a minimum of cost, and at 20 the same time to produce the toy in a durable and light form.

In the accomplishment of these results certain structural advantages inhere in the body or fuselage owing to the same together with the tail-plane and landing gear struts 25 being formed of one integral piece of sheet metal as hereinafter more clearly pointed out.

In the accompanying drawings,

Figure 1 is a plan view of the blank from 30 which the fuselage, tail-plane and landing gear struts are formed.

Fig. 2 is a side elevation of the fuselage, tail-plane and landing gear struts after form has been given the blank.

Fig. 3 is a section on the line 3—3 of Fig. 2.

Fig. 4 is a top plan view of Fig. 2, and

Fig. 5 is a front elevation of the toy as 40 completely formed, the same being a view looking at the front end of Fig. 2.

As shown in Fig. 1 the part 1 which is subsequently bent to form the body or fuselage, the part 2 which forms the tail plane and the parts 3 and 3' which form the landing gear struts are stamped from a single 45 sheet of metal such as tin, aluminum or other light material which admits of being struck up by means of suitable dies and to thereafter retain the complete air-ship form 50 when such is given the blank. In giving

the blank such form the edges 4—4 are turned downwardly and outwardly to form the fuselage the top of which is flat longitudinally. The landing gear struts 3—3' are turned downwardly and outwardly 55 from the edges 4—4 forward of the middle portion of the blank, the rearward struts 3' being extended downwardly from about midway of the said blank. The said landing gear struts are bent longitudinally to 60 impart strength thereto and at the lower ends on each side they come together and are integrally united to form bearings 8 for the axle 6 of the landing wheels 7. The tail-plane 2 is given its form when stamped, 65 with a slight downward and rearward curvature on each side of the center thereof as is indicated in Figs. 2 and 5. The parts thus formed by means of suitable dies are integral, and owing to the construction as 70 defined, the device meets all the requirements of a toy of this character, the principal one of which is the capacity thereof to float in the air for a very considerable distance after being thrown out into the air. 75 Besides this, the manufacture of the toy is greatly expedited owing to the features described and their manner of formation, and the cost is low. The durability of the toy likewise meets the character of usage usually given such toys.

While I have referred to sheet metal in the description, it will be readily seen that any suitable sheet material may be used. For example a suitable quality of card 85 board. I however, consider sheet metal the preferred material.

Having described the invention, I claim:

1. An airplane fuselage consisting of a longitudinal body open at the bottom with 90 landing gear struts at the forward end thereof, the said body and landing gear struts being formed of one integral piece of sheet material.

2. An air-ship toy, comprising a body or 95 fuselage, the tail-plane, and the landing gear struts formed from one integral piece of sheet material.

In testimony whereof I affix my signature.

DAVID H. BROOK.
